UNITED STATES PATENT OFFICE

GEORGE RAUF, OF COVINGTON, KENTUCKY

DESIGN FOR A MOUNTING FOR JEWELS

Application filed March 14, 1930. Serial No. 34,856. Term of patent 14 years.

To all whom it may concern:

Be it known that I, GEORGE RAUF, a citizen of the United States, residing at Covington, in the county of Kenton, and State of Kentucky, have invented a new, original, and ornamental Design for Mounting for Jewels; of which the following is a specification, reference being had to the accompanying drawing, forming part thereof.

I claim:

The ornamental design for a mounting for jewels, as shown.

GEORGE RAUF.
